UNITED STATES PATENT OFFICE.

WILLIAM H. COX, OF COLLEGEVILLE, PENNSYLVANIA.

MOP-CLOTH.

1,387,472.

Specification of Letters Patent. Patented Aug. 16, 1921.

Application filed September 10, 1920. Serial No. 409,439.

To all whom it may concern:

Be it known that I, WILLIAM H. Cox, a citizen of the United States, residing at Collegeville, in the county of Montgomery and State of Pennsylvania, have invented 5 certain new and useful Improvements in Mop - Cloths, of which the following is a specification.

One object of my present invention is to 10 provide an improved mop cloth which will be particularly adapted for use in connection with mops employing wringing rollers such for example as a mop of the type disclosed in my co-pending application for 15 United States Patent Serial No. 387,883.

Another object is to so construct my improved mop cloth that all of its parts can be made to freely pass between the wringing rollers during the wringing action of 20 the mop and so that all of said parts may be moved into operative mopping position to permit wear on all portions of the cloth to prolong its life and utility.

These objects, and other advantageous 25 ends which will be described hereinafter, I attain in the following manner, reference being had to the accompanying drawings in which—

Figure 1 is a face view of a mop cloth 30 made in accordance with my invention,

Fig. 2 is an enlarged section taken on the line 2—2 of Fig. 1, and

Fig. 3 is a view of the same general character as Fig. 1 showing a slight modification 35 in the manner of securing together the spirally wound layers of the fabric.

Referring to the drawings and particularly to Figs. 1 and 2, my improved mop cloth includes a strip 4 of flexible material 40 which is preferably made of absorbent fabric either woven or knitted. This strip as shown in Fig. 2 is wrapped in spiral formation layer upon layer until a desired thickness is obtained. After which the layers 45 are stitched or sewed together with rows 5 of stitching to make a unitary structure. The rows of stitching are spaced apart as shown in Fig. 1. Thus the various layers

are stitched together at numerous points and when used in a mop as above described a 50 band is produced which can be freely run continuously between the wringing rollers without obstruction and when one part of the cloth starts to wear, a new portion can be moved into operative position so that the 55 entire mop cloth can be used for mopping purposes. Furthermore by arranging the stitching as above described when wear does occur the wear will be practically confined to areas between adjacent parts of the stitching so that even though holes are worn in the outer layers they will not interfere with the continued use of the cloth.

In Fig. 3 of the drawing instead of showing continuous rows of stitching I have 65 illustrated tufts or tacks 5^a as a means for securing together the layers at various points throughout the entire cloth. In all other respects the structure shown in Fig. 3 is similar to that disclosed in connection 70 with Figs. 1 and 2.

While I have described my invention as taking a particular form, it will be understood that the various parts of my invention may be changed without departing 75 from the spirit thereof, and hence I do not limit myself to the precise construction set forth, but consider that I am at liberty to make such changes and alterations as fairly come within the scope of the appended 80 claim.

Having thus described my invention, what I claim as new and desire to secure by Letters Patent is:—

A mop in the form of an endless loop 85 comprising a strip of fabric wound in superposed layers with the layers stitched together.

In testimony whereof I have signed my name to this specification in the presence of 90 two subscribing witnesses.

WILLIAM H. COX.
